ATTORNEY.

UNITED STATES PATENT OFFICE.

WILLIAM W. ROSSMAN, OF DETROIT, MINNESOTA.

STOVE OR FURNACE.

SPECIFICATION forming part of Letters Patent No. 601,590, dated March 29, 1898.

Application filed August 10, 1897. Serial No. 647,722. (No model.)

To all whom it may concern:

Be it known that I, WILLIAM W. ROSSMAN, a citizen of the United States, residing at Detroit, in the county of Becker and State 5 of Minnesota, have invented certain new and useful Improvements in Stoves or Furnaces; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to improvements in stoves and furnaces, and has particular reference to that class of stoves and furnaces that are used to heat the room or space in which they are located, and has for its object the provision of an increased air-heating surface 20 for the purpose of bringing into contact with the heat of the stove or furnace the greatest possible amount of air.

The invention consists, essentially, of a 25 number of tubes or pipes arranged inside of the fire-box and smoke-chambers of the stove or furnace, along the sides thereof, and extend from the bottom of the stove up through the fire-box and smoke-chambers and through 30 the top of the stove and are adapted to take air from the bottom, heat it, and throw it out at the top.

The invention further consists in the novel 35 construction and arrangement of the several parts of the device, as hereinafter described, illustrated in the drawings, and more particularly pointed out in the claims hereunto appended.

In the drawings, Figure 1 is a perspective 40 view of a stove having my improvement applied thereto and having a portion of the casting of said stove broken away to show the tubing in the fire-box and smoke-chambers. Fig. 2 is a longitudinal sectional view of Fig. 1. Fig. 3 is a rear end sectional view of the 45 device, showing the arrangement of the tubes. Fig. 4 shows different forms of pipes or tubes that I use in stoves for the purpose of increasing the air-heating surface.

50 Referring to the drawings by letter, A represents the body of the stove or furnace, and A' the legs or supports therefor, as shown.

B is the ash-receptacle, and G the grate between the fire-box and the said ash-receptacle.

B' is a door through which the ashes are 55 removed, and A² is the main fuel-door to the fire-box.

The upper part of the stove or furnace is divided into two or more smoke chambers or 60 passages R and S, made by the partitions or plates R' and S', as shown. The entrance to the chamber S is at the rear end of the stove, the smoke and flame passing thereto from the fire-box, and the entrance into the smoke-chamber R being at the front part of the 65 stove, the flame and smoke passing from the chamber S into the chamber R, from whence it is conducted through the outlet-flue or chimney.

S² is a door in the front part of the stove or 70 furnace leading into the chamber S and is for the purpose of removing soot and ashes therefrom, and R² is a door in the rear of the stove and leads into the chamber R and is for the purpose of cleaning said chamber. 75 The passages between the fire-box and chamber S and between chamber S and chamber R are afforded by reason of the plates S' and R' being shorter than the interior of the stove. Instead of these plates being short, 80 as described, they may be the full length of the interior of the stove and provided with suitable openings, as is evident.

C C C C are a number of tubes extending 85 through said stove or furnace from the bottom to the top thereof, passing through the fire-box and the two or more smoke-chambers S and R, as is evident. The lower ends of these tubes or pipes extend a short distance below the bottom of the stove and are slightly 90 flared, as shown at C', to induce a freer passage of the air thereto, as is evident. The upper ends of these tubes may be flush with the top of the heater or stove or they may project a slight distance above, as desired. 95 The tubes C C C C instead of being the same size in the smoke-chambers as in the fire-box are larger, as shown at C².

By enlarging the tubes or conduits in the 100 chambers R and S a greater amount of heating-surface for heating the air in its passage through said tubes or conduits is obtained, and the enlargement of the tubes or conduits also serves to greatly diminish the space for

the passage of the products of combustion through said chambers, so that the passage of said products will be necessarily slow or retarded, whereby a more complete mingling, and therefore combustion, of the escaping gases will be had, and thus the air in its passage through the tubes or conduits will be delivered into the room in a more highly-heated condition. It will be observed that the outlets of the tubes or conduits are somewhat contracted, which admits of a more rapid flow of air into the room and its circulation therein.

The fire having been started in the fire-box, the tubes C C therein will become heated and the contained air will rise and flow from the upper ends of the tubes, thus drawing into the lower ends cool air, which in turn is heated and thrown out into the room of space. By reason of the tubes passing through the smoke-chambers the heat therein will be partially absorbed and thrown out into the room instead of escaping through the chimney. Instead of the enlargement of the tubes C², I may have the enlargements C³ C³, one in each smoke-chamber, as is evident.

Having thus described my invention, what I claim is—

1. In a stove or heater of the character described, the combination with the fire-box and the chambers S and R, of air tubes or conduits leading from the outside, near the bottom of the stove or heater, and passing up through the fire-box and the chambers S and R, said tubes or conduits being enlarged in said chambers, whereby the products of combustion are retarded in their passage through said chambers and the air in passing through the tubes or conduits is highly heated, as set forth.

2. The combination with the fire-box and the chambers S and R, of the air tubes or conduits passing through the ash-chamber, the fire-pot and the chambers S and R, said tubes or conduits being enlarged in the chambers S and R and having contracted outlets, whereby the cold air taken in at or near the bottom of the stove is delivered into the room rapidly and in a highly-heated condition, as set forth.

In testimony whereof I affix my signature in presence of two witnesses.

WILLIAM W. ROSSMAN.
